GAS BLAST CIRCUIT BREAKER

Leon R. Ludwig, Wilkinsburg, and Benjamin P. Baker, Turtle Creek, Pa., assignors to Westinghouse Electric Corporation, East Pittsburgh, Pa., a corporation of Pennsylvania

Application November 28, 1944, Serial No. 565,456

34 Claims. (Cl. 200—148)

1

This invention relates to circuit interrupters, in general, and, more particularly to circuit interrupters which utilize a gas under pressure to effect the extinction of one or more arcs drawn within the circuit interrupter.

A general object is to provide an improved circuit interrupter of the gas blast type in which improved mounting constructions are employed to render improved performance with a more safe and rugged construction.

A more specific object is to adapt the dead tank oil circuit interrupter casing to a circuit interrupter of the compressed gas type in which the casing may in certain instances be pressurized. Preferably, exhaust passages are provided through the bushings which enter the casing and which support on their interior ends arc extinguishing units thus disposed within the casing.

Another object is to provide an improved circuit interrupter which interrupts the three phases of a transmission system and in which arc extinguishing units associated with the several poles of the breaker are disposed within a pressurized casing which is preferably a grounded metal tank.

Another object is to provide an improved circuit interrupter of the compressed gas type which is disposed within a grounded metal casing, and in which the cross-bar is used to initiate the opening of the contacts of the arc extinguishing units disposed within the casing. In certain instances, it is advisable to pressurize the casing and to permit the compressed gas to exhaust through bushings extending into the casing and supporting on their interior ends arc extinguishing units.

Another object is to provide an improved compressed gas circuit interrupter which is supported within a pressurized casing and to provide improved arc extinguishing units disposed within the casing to more effectively interrupt the electrical circuit passing therethrough.

Another object is to provide an improved circuit interrupter of the compressed gas type in which the arc extinguishing units are disposed in a pressurized casing and in which a blast valve is operated by a cross-bar. After a predetermined movement of the blast valve, the arcing contacts are separated so as to enable the blast of gas to effect the extinction of the arc drawn adjacent the arcing contacts.

Further objects and advantages will readily become apparent upon a reading of the following specification taken in conjunction with the drawings; in which:

Figure 1 is a vertical sectional view taken 55 from good solid metal supports.

through a circuit interrupter embodying our invention, the casing not being pressurized, and the contacts being shown in the closed-circuit position;

5 Fig. 2 is a view similar to that of Fig. 1 in which the casing is pressurized, again the contacts being shown in the closed-circuit position;

Fig. 3 is a vertical sectional view through a circuit interrupter embodying our invention, the casing being pressurized and the arc extinguishing units being of improved construction;

Fig. 4 is a view similar to Fig. 3 but showing a modified type of arc extinguishing unit;

10 Fig. 5 is a modified type of compressed gas circuit interrupter embodying our invention, the contacts being shown in the closed-circuit position and the arc extinguishing units being of modified construction;

Fig. 6 is an enlarged view of the right-hand 20 arc extinguishing unit of Fig. 5, the contacts being shown in the partially open circuit position;

Fig. 7 is a modified type of compressed gas circuit interrupter embodying our invention, the arc 25 extinguishing units being of a modified construction;

Fig. 8 is a plan view of the circuit interrupter shown in Fig. 9;

Fig. 9 is a vertical sectional view of the circuit 30 interrupter shown in Fig. 8 taken along the line IX—IX of Fig. 8, the contacts being shown in the closed-circuit position; and

Fig. 10 is a sectional view taken along the line X—X of Fig. 9.

35 In the circuit interrupter of our invention we propose to incorporate advantages which have heretofore been found only in conventional dead tank high voltage oil circuit breaker. Some of these advantages are as follows:

40 1. Structural stability; the use of steel to support all the breaker parts.

2. Inherent geometry of the design to place all live parts above reach without adding deliberately to the minimum height of the breaker.

45 3. Through type current transformers, in conjunction with the bushings are obtained at very little additional cost.

4. Potential devices may be obtained at very little additional cost.

50 5. The porcelain insulation is supported so that it is subjected to compression forces only, and may easily be resiliently mounted to withstand shock.

6. Minimum lengths of porcelains protrude

7. In case of servicing, all parts needing attention are inside and protected from the weather.

8. The pole unit operating mechanism is at ground potential, and thus the auxiliary switch may be directly connected.

In our invention we propose to provide an improved compressed gas circuit interrupter using a metal enclosure or casing as shown in Fig. 1 which possesses all the above advantages and more. Referring more particularly to this figure, it will be observed that the reference numeral 1 designates a casing, in this instance formed of metal, in which the enclosed region 2 is not pressurized, but is preferably at atmospheric pressure. Supported from the cover 3 of the casing 1 are bushings 4, 5 which are preferably of the condenser high voltage type.

Supported at the interior ends of the bushings 4, 5 are arc extinguishing units generally designated by the reference numeral 6. Exhaust passages 7 may extend through the bushings 4, 5 which may be utilized in exhausting the contaminated compressed gas to the region exterior of the casing 1 after said gas has been utilized to effect the extinction of the arc drawn in each unit 6. A cross-bar 8 electrically connects the two units 6 in the closed circuit position of the interrupter as shown by the full lines in Fig. 1.

The cross-bar 8 is reciprocally operated by an insulating operating rod 9 having a piston 10 secured to its upper end. The piston 10 operates within a piston chamber 11 having inlet openings 12, 13 associated therewith. It will be noted that compressed gas entering the inlet opening 12 will force the piston 10 and cross-bar 8 downwardly to effect the opening operation of the interrupter, whereas compressed gas entering the inlet opening 13 will force the piston 10 upwardly to thereby effect the closing operation of the interrupter. Other types of pole unit mechanism may be used.

An insulating conduit 14 associated with the inlet opening 12 is utilized to conduct compressed gas to the two arc extinguishing units 6 during the opening operation.

Each unit 6 comprises a contact foot 15 which is preferably clamped by clamping means 16 to the interior or lower end of the bushing 4 or 5. The contact foot 15 has an orifice-shaped stationary contact 17 associated therewith which cooperates with a rod-shaped movable contact 18 in the closed circuit position as shown.

Secured to the lower end of each movable contact 18 is a pair of resilient fingers 19, which frictionally engage the opposed outer ends of the conducting cross-bar 8. A flange 20 is rigidly secured to the movable contact 18 and serves as an upper seat for a compression-spring 21 which biases the movable contact 18 toward its closed-circuit position. Guide fingers 22 may be provided to guide the movable contact 18 during its reciprocating vertical travel. Preferably, the guide fingers 22 are pivotally mounted at 23 and are spring-biased inwardly by suitable means not shown.

During the opening operation compressed gas is admitted by suitable means not shown to the inlet opening 12. Here it acts to force the piston 10 and cross-bar 8 downwardly and also passes downwardly through the conduit 14 into the insulating casing 24 of the unit 6. It will be observed that downward motion of the cross-bar 8 by means of the frictional engagement with the fingers 19 causes downward opening movement of the movable contact 18 against the upward bias-

ing action of the compression spring 21. This draws an arc between the upper end of the contact 18 and the stationary contact 17, which arc is extinguished by a blast of compressed gas passing downwardly through the conduit 14 into the casing 24 and outwardly to the region exterior of the casing 1 through the exhaust passage 7 provided within the bushing 5.

After the arc is extinguished, further downward movement of the cross-bar 8 causes a disengagement thereof from the fingers 19 to introduce two isolating gaps into the circuit controlled by the interrupter, the cross-bar finally reaching its full open circuit position as indicated by the dotted lines 25 of Fig. 1.

In the meantime, the compression spring 21 has retracted the movable contact 18 to its closed-circuit position in which it engages the orifice-shaped stationary contact 17. To effect a closing of the interrupter, compressed gas is forced through the inlet 13 to move the piston 10 and cross-bar 8 upwardly. This effects an engagement between the opposed outer ends of the cross-bar 8 and the fingers 19 to thereby complete the electrical circuit through the interrupter.

It will be observed that in the above construction, conventional bushing terminals with their current transformers 26 and potential devices 26a may be employed, protruding from the top of the metal casing 1. Depending from the lower end of each bushing is the compressed air interrupter. The contacts are actuated by a traverse 8 similar to that used in an oil breaker. The first part of the motion of the traverse causes the arcing contacts to part. By the time the arc has been extinguished the continued motion of the traverse 8 forms two isolating air gaps between the interrupters the same as in an oil breaker.

Indicating equipment generally designated by the reference numeral 30 may be employed in conjunction with the auxiliary switch 8 to indicate both the fully open and fully closed positions of the interrupter.

If the metal enclosure or casing 1 is operated at atmospheric pressure as described, the compressed gas may be taken from a suitable storage reservoir, not shown, through one or more blast valves and through suitable gas passages into the interrupters. After passing through the interrupters it may be discharged into the casing 1 or preferably it may be discharged through the hollow terminal bushings 4, 5 as shown, to the region exterior of the casing 1.

If the enclosure or casing 1 is pressurized as shown in Fig. 2, the size of the entire structure except for the bushings can be decreased somewhat in proportion to the absolute pressure, in that the striking distances go down inversely with the pressure. The practical limit in striking distances may be assumed as that which is necessary to hold for a short time line to ground voltage plus a 25% overshoot in voltage if for some reason the enclosure 1 lost its pressure. At higher pressures the striking distances would be less than required by oil.

In our invention the compressed gas or air for operating the breaker and interrupting the arc may come from an external storage reservoir as in Fig. 1 and after passing through the arc may be discharged to atmospheric pressure through the hollow terminal bushings 4, 5 or some other passage. But, preferably, it may be taken directly from the pressurized enclosure or casing 1 as shown in Fig. 2. In this event it will pass

through conduits 14 into the units 6 and discharge through the hollow bushing terminals 4, 5 by means of the discharge or exhaust passages 7.

Referring more particularly to Fig. 2 it will be observed that the casing 1 is pressurized so that the distances between the units 6 and the casing 1 may be considerably reduced. Also the isolating gap distances may be decreased. By actuating the solenoid 27 by energizing the coil 28, pilot valve 29 may be lowered to permit high pressure gas from the casing 1 to act on the top side of piston 30 which is secured to the upper end of the stem 31 of blast valve 32. The opening of the blast valve 32 permits high pressure gas from the casing 1 to flow past the valve seat 33 into the region 34. Here it both acts on the top face of the piston 10 and through the conduit 14 leading to the two units 6. The opening operation of the interrupters 6 is the same as previously described; consequently, a further description thereof appears unnecessary. Again the exhaust gas is discharged from the casing 1 through the exhaust passages 7 provided in the bushings 4, 5.

The arc extinguishing units may be of the type shown in Figs. 1 or 2 or transverse splitters 35 may be employed as shown in Fig. 3.

In Fig. 3 a modified type of arc extinguishing unit, generally designated by the reference numeral 36, is employed. A rod-shaped movable contact 37 is secured by frictional engagement to the outer end of the cross-bar 8 and cooperates with a flat leaf-shaped stationary contact 38, the latter terminating at its right-hand end with a conducting tube 39 which passes through the bushing 5.

Consequently, during the opening operation, an arc is drawn between the upper end of the movable contact 37 and the stationary contact 38 past the horizontally disposed insulating splitters 35 to effect the extinction thereof. The exhaust gases pass upwardly out of the casing 1 through the exhaust passages 7.

From the above operation, it will be apparent that following separation between the ends of the cross-bar 8 and the fingers 19 secured to the movable rod-shaped contact 37, two isolating gaps in the circuit are thereby provided and the compression spring 21 serves as in the prior embodiments of our invention to effect a retraction of the movable contact 37 to its closed position in which it engages the strap 38. Consequently, the cross-bar 8 moves downwardly to the position indicated by the dotted lines 25.

It will be observed that the arc extinguishing unit 36 is composed entirely of insulating material with the exception of the strap 38. Also it will be observed that the cross-bar 8 continues its downward movement to the position indicated by the dotted lines 25 in Fig. 3 to effect two isolating gaps in the circuit. The operating arrangement is the same as previously described in connection with Fig. 2.

In Fig. 4 a modified type of arc extinguishing unit 40 is employed having gas-evolving insulating means 41 defining a passage 42 of cylindrical shape through which the movable contact 18 may be drawn during the opening operation. Again a compression spring 21 biases the contact 18 toward its closed position and fingers 19 frictionally engage the cross-bar 8 during a portion of the latter's opening travel. The operating ar-

rangement may be the same as described in connection with Figs. 2 and 3.

During the opening operation, opening of the blast valve 32 permits the compressed gas or air within the casing 1 to force the piston 10 and cross-bar 8 downwardly. Also compressed gas flows downwardly through the conduit 14 into the unit 40. The downward motion of cross-bar 8 making frictional engagement with the fingers 19 forces the movable contact 18 downwardly away from the stationary contact 17 against the upward biasing action exerted by the compression spring 21. The arc thus drawn between the contacts 17, 18 is drawn through the cylindrical passage 42. Within this passage the arc causes the evolution of gas from the insulating material lining the walls of the passage 42 which assists high current interruption.

The advantages thus gained by the foregoing constructions are as follows:

1. We have provided a smaller, cheaper and more rugged construction than the conventional outdoor compressed air circuit interrupter.

2. An enclosure comparable to the conventional oil breaker is made possible by the high dielectric strength of fluid under pressure.

3. An inside isolating gap as short as that in an oil circuit breaker may be employed which is only a small fraction of the length required by conventional air circuit breakers.

4. A direct connection for the auxiliary switch operating mechanism may be provided.

5. Higher speed interruption, isolation and reclosing is made possible by decreased dimensions, resulting from all live parts operating in a high pressure, clean, dry atmosphere.

6. Cheaper current transformers and potential devices may be employed.

7. Porcelain insulation may be employed which is better supported than heretofore and is placed in compression.

In order to obtain high speed interruption, it is necessary to place the blast valve as close to the interrupter as possible so that very little or no time will be required to fill the air passage between the blast valve and the interrupter. The constructions shown in Figs. 5 and 7 are such that little time is required for the air to reach the interrupting orifices. Referring to Fig. 5 it will be observed that a blast valve 43 has a portion 44 constituting a piston surface. The blast valve 43 slidably operates within a chamber 45 supported by suitable means not shown from the wall of the casing 1. The cross-bar 8 during its downward movement frictionally engages fingers 19 disposed at the lower end of a stem 46 having secured thereto at the upper end thereof a pilot valve 47 closing an opening 48 in the blast valve 43. A compression spring 49 biases the pilot valve 47 upwardly toward its closed position.

Consequently, the initial downward movement of the stem 46, caused by the frictional engagement between the fingers 19 and the cross-bar 8, discharges the compressed gas within the region 50 through the opening 48, through the tubular movable contact 51 and through the exhaust passage 7 to the region exterior of the casing 1. This dumping of the air below the blast valve 43 by operation of the pilot valve 47 permits the high pressure gas within the casing 1 to act on the piston surface 44 forcing the blast valve 43 downwardly.

After a predetermined downward movement of the blast valve 43, the inwardly extending portion 52 thereof strikes a flange 53 integrally formed with the movable contact 51 to cause downward

movement of the movable contact 51. This draws an arc between the contacts 51, 17 which is extinguished by a flow of compressed gas passing past the blast valve 43 and out of the bushing 5 through the exhaust passage 7.

Continued downward movement of the cross-bar 8 causes a disengagement thereof from the fingers 19. This creates two isolating disconnect gaps in the circuit and permits the compression springs 49, 54 and 63 to effect a retraction of the movable parts of the modified arc extinguishing unit 55. The bleeder opening 56 provided in the chamber 45 permits high pressure gas to leak from the casing 1 into the region 50 below the blast valve 43.

Consequently, in this modification of our invention, we have provided means for omitting the conduit 14 and for providing a very short distance between the seat of the blast valve and the interrupting orifice.

Fig. 6 shows in a more clear manner the initial opening movement of the movable parts of the arc extinguishing unit 55.

The modified type of arc extinguishing unit 57 as shown in Fig. 7 operates in a manner somewhat similar to that previously described in connection with Figs. 5 and 6. The unit 57 comprises an insulating casing 58 having a guide spider 59 disposed therein which serves to guide the vertical reciprocating motion of a movable contact 60 biased upwardly by a compression spring 61. Again the cross-bar 8 initially operates by frictional engagement a pilot valve 47 which normally closes an opening 48 provided in the blast valve 43. The blast valve 43 is biased against its seat 62 by a compression spring 63. During the opening operation the cross-bar 8 moves downwardly causing opening of the pilot valve 47 thus dumping the air below the blast valve 43. The high pressure gas within the casing 1 acts on the surface area 44 through the apertures 64 provided in the casing 65 to force the blast valve 43 downwardly against the upward biasing action exerted by the compression spring 63.

After a predetermined downward travel of the blast valve 43 the inwardly extending portion 63 thereof strikes the flange 67 secured to the movable contact 60 causing opening motion of the same, thereby drawing an arc between the contacts 17, 60. Meanwhile, the compressed gas within the casing 1 has passed the seat 62 and has flowed upwardly into the region 58 adjacent the contact structure. Thus when the contact 60 separates from the stationary contact 17 to draw an arc, the high pressure gas now within the region 58 effects the extinction of this arc, the contaminated gas passing upwardly through the exhaust passage 7 and out of the casing 1 through the bushing 5.

Further downward movement of the cross-bar 8 to the position 25 permits the compression springs 63, 61 and 49 to effect retraction of the movable parts of the unit 57, the bleeder opening 56 again permitting high pressure gas within the casing 1 to enter the region 50 below the blast valve 43. Consequently, in the open circuit position of the interrupter the contacts are closed and the cross-bar 8 provides two isolating gaps in the circuit.

Figs. 8, 9 and 10 illustrate a circuit interrupter embodying our invention in which the three poles of the breaker, each pole containing two units serially connected, are positioned within the pressurized casing 70. The two units of each

pole of the breaker are preferably of the type designated by the reference numeral 55 of Fig. 5 and operate in the same manner. The operating rod 71, composed of insulating material, effects a simultaneous downward movement of the three cross-bars 8 associated with the three poles of the breaker as indicated in Fig. 10. Again the exhaust gases pass through the bushings 4, 5 to the region exterior of the casing 70. An insulating support 72 structurally interconnects the three cross-bars 8 with the insulating operating rod 71 which is schematically shown to be operated by a winding 73 and a solenoid 74. If desired insulating cylinders 75 may be employed to assist in electrically isolating the several arc extinguishing units 55.

From the foregoing description it will be apparent that in this modification of our invention we have provided an economical and space saving arrangement in which reduced dimensions are possible in the circuit breaker by employing a pressurized casing 70 in which the interrupting units of the three poles may be placed. By employing a single casing 70 for the three poles of the breaker mounting space is reduced, material is saved, and inspection is facilitated.

From the foregoing description of several embodiments of our invention, it will be apparent that we have invented a compressed gas circuit interrupter of novel construction which takes advantage of all of the desirable features of dead tank oil circuit breaker mounting constructions, but yet has additional advantages inasmuch as the enclosure or casing may be pressurized to reduce the dimensions of the interrupter. The mounting constructions which we have shown thus result in economical saving of material, rigid construction, and yet are such that inspection may be easily permitted. The arc extinguishing units may be of different types and although we have shown a few particular types, it is to be clearly understood that the scope of our invention is broad and is not confined to the particular type of extinguishing units which we have described.

Although we have shown and described specific structures, it is to be clearly understood that the same were merely for the purpose of illustration and that changes and modifications may readily be made therein by those skilled in the art without departing from the spirit and scope of the appended claims.

We claim as our invention:

1. In a circuit interrupter of the compressed gas type, a casing containing gas at substantially atmospheric pressure, two bushings extending into the casing and having exhaust passages extending therethrough, an arc extinguishing unit disposed adjacent the interior end of each bushing, a cross-bar disposed within the casing and electrically interconnecting the units in the closed circuit position, a movable contact associated with each unit, means for forcing gas adjacent the movable contact of each unit, valve means other than the movable contacts for controlling the flow of gas, the cross-bar causing the opening movement of the movable contact during the initial portion of its opening travel, and means for reclosing the contacts after the cross-bar has established the isolating gaps.

2. In a compressed gas circuit interrupter, a casing, a bushing extending into the casing and having an exhaust passage extending therethrough, an arc extinguishing unit disposed adjacent the interior end of the bushing, a sta-

tionary orifice-shaped contact, a movable contact cooperable with the stationary contact to establish an arc, a cross-bar, means biasing the movable contact toward its closed circuit position, a conduit for compressed gas leading into the unit, valve means other than the movable contact for controlling the flow of gas through the conduit, and the initial opening movement of the cross-bar causing opening movement of the movable contact.

3. In a circuit interrupter of the compressed gas type, a casing containing gas at substantially atmospheric pressure, two bushings leading into the casing and having exhaust passages extending therethrough, each bushing supporting adjacent its interior end an arc extinguishing unit, a cross-bar, a stationary orifice-shaped contact and a movable contact associated with each unit, means biasing each movable contact toward its closed position against the stationary contact, a conduit for conducting compressed gas into the two units, valve means other than the movable contacts for controlling the flow of gas through the conduit, the cross-bar causing the opening movement of both movable contacts during the initial opening movement of the cross-bar, and the cross-bar subsequently introducing two isolating gaps into the circuit controlled by the interrupter.

4. In a compressed gas circuit interrupter, a casing containing gas under pressure, two bushings extending into the casing and having exhaust passages leading therethrough, an arc extinguishing unit supported adjacent the interior end of each bushing, a cross-bar, a movable contact associated with each unit, means whereby the initial opening movement of the cross-bar causes the opening movement of each movable contact associated with each unit, said last-mentioned means also causing reclosure of the contacts of each unit after establishment of the isolating gaps by the cross-bar, and valve means other than the movable contacts for controlling the flow of gas adjacent a movable contact.

5. In a compressed gas circuit interrupter, a casing containing gas under pressure, two bushings extending into the casing and having exhaust passages leading therethrough, a substantially enclosed arc extinguishing unit supported adjacent the interior end of each bushing, a cross-bar, a movable contact associated with each unit, and the initial opening movement of the cross-bar causing the opening movement of each movable contact associated with each unit, a stationary orifice-shaped contact associated with each unit, means biasing each movable contact toward its respective stationary contact, and valve means other than the movable contacts for controlling the flow of gas from the casing through the two orifice-shaped contacts.

6. In a circuit interrupter of the compressed gas type, a casing containing gas under pressure, six bushings extending into the casing having exhaust passages extending therethrough, an arc extinguishing unit disposed adjacent the interior end of each bushing, a conducting cross-bar electrically interconnecting two units of each pole of the interrupter, and means for simultaneously operating the three cross-bars, contact structure disposed within each unit, and the initial opening movement of the cross-bar for each pole causing opening movement of the contact structure for the two units associated with that pole.

7. In a circuit interrupter of the compressed gas type, a casing containing gas under pressure, a bushing extending into the casing and having

an exhaust passage extending therethrough, an arc extinguishing unit disposed adjacent the interior end of the bushing, means of gas evolving material defining a cylindrical passage within the unit and in communication with the aforesaid exhaust passage, means for drawing an arc within the unit through the cylindrical passage, and valve means other than said last-mentioned means for controlling the flow of gas from within the casing through the cylindrical passage to exhaust out through the bushing.

8. In a circuit interrupter of the gas blast type, a casing containing gas under pressure, a bushing extending into the casing and having an exhaust passage therethrough, an arc extinguishing unit disposed adjacent the interior end of the bushing, a blast valve, a pilot valve, a cross-bar, the initial opening movement of the cross-bar operating the pilot valve to cause a dumping of gas in back of the blast valve.

9. In a circuit interrupter of the gas blast type, a casing containing gas under pressure, a bushing extending into the casing and having an exhaust passage therethrough, an arc extinguishing unit disposed adjacent the interior end of the bushing, a blast valve, a pilot valve, a cross-bar, the initial opening movement of the cross-bar operating the pilot valve to cause a dumping of gas in back of the blast valve, a movable tubular contact through which the gas is dumped, and the blast valve opening the movable contact after a predetermined opening travel.

10. In a circuit interrupter of the gas blast type, a casing containing gas under pressure, a bushing extending into the casing and having an exhaust passage therethrough, an arc extinguishing unit disposed adjacent the interior end of the bushing, a blast valve, a pilot valve, a cross-bar, the initial opening movement of the cross-bar operating the pilot valve to cause a dumping of gas in back of the blast valve, an orifice-shaped stationary contact, a movable rod-shaped contact, and the blast valve opening the movable contact after a predetermined opening travel of the blast valve.

11. In a circuit interrupter of the compressed gas type, a casing, a pair of bushings extending into the casing and having arc extinguishing units disposed adjacent their interior ends, a conducting cross-bar for electrically interconnecting the units in the closed circuit position of the interrupter, contact structure associated with each unit to establish an arc, valve means other than the contact structure to control the flow of gas adjacent the arc, and means whereby the cross-bar causes initial opening of the contact structure to establish arcing and permits reclosure of the contact structure while the cross-bar continues its opening movement to insert two isolating gaps in the circuit.

12. In a circuit interrupter of the compressed gas type, a casing containing gas under pressure, a pair of bushings extending into the casing and having arc extinguishing units disposed adjacent their interior ends, a conducting cross-bar for electrically interconnecting the units in the closed circuit position of the interrupter, contact structure associated with each unit to establish an arc, valve means other than the contact structure to control the flow of gas adjacent the arc, and means whereby the cross-bar causes initial opening of the contact structure to establish arcing and permits reclosure of the contact structure while the cross-bar continues its opening movement to insert two isolating gaps in the circuit.

13. In a circuit interrupter, a casing, two bush-

ings extending within the casing and having arc extinguishing units disposed adjacent their interior ends, contact structure associated with each unit biased to the closed circuit position, a conducting cross-bar electrically interconnecting the two units in the closed circuit position of the interrupter, momentary engaging means for permitting initial opening motion of the cross-bar to cause initial separation of the contact structure of each unit, the contact structure reclosing following extinction of the arcs, and the continued opening motion of the cross-bar inserting two isolating gaps in the circuit.

14. In a circuit interrupter, a casing containing gas under pressure, two bushings extending within the casing and having arc extinguishing units disposed adjacent their interior ends, contact structure associated with each unit biased to the closed circuit position, a conducting cross-bar electrically interconnecting the two units in the closed circuit position of the interrupter, momentary engaging means for permitting initial opening motion of the cross-bar to cause initial separation of the contact structure of each unit, the contact structure reclosing following extinction of the arcs, and the continued opening motion of the cross-bar inserting two isolating gaps in the circuit.

15. In a circuit interrupter of the compressed gas type, a casing containing gas under pressure, a bushing extending into the casing and having an arc extinguishing unit disposed adjacent its interior end, contact structure including an orifice-shaped stationary contact and a movable contact separable from the stationary contact to establish an arc, an annular blast valve surrounding the movable contact and making abutting engagement with the stationary contact, and disconnect means for causing operation of the blast valve prior to contact separation and making only momentary engagement therewith.

16. In a circuit interrupter of the compressed gas type, a casing containing gas under pressure, a bushing extending into the casing and having an arc extinguishing unit disposed adjacent its interior end, contact structure including an orifice-shaped stationary contact and a movable contact separable from the stationary contact to establish an arc, an annular blast valve surrounding the movable contact and making abutting engagement with the stationary contact, disconnect means for causing operation of the blast valve, and a lost-motion connection between the blast valve and the movable contact.

17. In a circuit interrupter of the compressed gas type, a casing containing gas under pressure, a bushing extending into the casing and having an arc extinguishing unit disposed adjacent its interior end, contact structure including an orifice-shaped stationary contact and a movable contact separable from the stationary contact to establish an arc, an annular blast valve surrounding the movable contact and making abutting engagement with the stationary contact, a pilot valve, and the disconnect means causing operation of the pilot valve.

18. In a circuit interrupter of the compressed gas type, a casing containing gas under pressure, a bushing extending into the casing and having an arc extinguishing unit disposed adjacent its interior end, contact structure including an orifice-shaped stationary contact and a movable contact separable from the stationary contact to establish an arc, an annular blast valve surrounding the movable contact and making abutting engagement with the stationary contact, a pilot 75

valve, the disconnect means causing operation of the pilot valve, and a lost-motion connection between the blast valve and the movable contact.

19. In a circuit interrupter of the compressed gas type, a casing containing gas under pressure, an arc extinguishing unit disposed within the casing, movable contact structure separable to establish an arc, a blast valve, disconnect means operable to cause opening of the blast valve, and a lost-motion mechanical connection between the blast valve and the movable contact structure.

20. In a circuit interrupter of the compressed gas type, a casing containing gas under pressure, an arc extinguishing unit disposed within the casing, a stationary contact cooperable with a movable contact to establish an arc, a blast valve for admitting gas within the casing toward the stationary contact prior to contact separation, disconnect means, and the disconnect means causing operation of the blast valve and making only momentary engagement therewith.

21. In a circuit interrupter of the compressed gas type, a casing containing gas under pressure, an arc extinguishing unit disposed within the casing, a stationary contact cooperable with a movable contact to establish an arc, a blast valve for admitting gas within the casing toward the stationary contact, a pilot valve for dumping gas below the blast valve, disconnect means, and the disconnect means causing operation of the pilot valve and making only momentary engagement therewith.

22. In a circuit interrupter of the compressed gas type, a casing containing gas under pressure, a bushing extending within the casing and having an exhaust passage therethrough, an arc extinguishing unit disposed within the casing adjacent the interior end of the bushing, an orifice-shaped stationary contact cooperable with a movable contact to establish an arc, a blast valve for admitting gas within the casing toward the stationary contact prior to contact separation, disconnect means, and the disconnect means causing operation of the blast valve and making only momentary engagement therewith.

23. In a circuit interrupter of the compressed gas type, a casing containing gas under pressure, a bushing extending within the casing and having an exhaust passage therethrough, an arc extinguishing unit disposed within the casing adjacent the interior end of the bushing, an orifice-shaped stationary contact cooperable with a movable contact to establish an arc, a blast valve for admitting gas within the casing toward the stationary contact and out the bushing, a pilot valve for dumping gas below the blast valve, disconnect means, and the disconnect means causing operation of the pilot valve.

24. In a circuit interrupter of the compressed gas type, a casing, a pair of bushings extending into the casing and having arc extinguishing units disposed adjacent their interior ends, at least one of the bushings having an exhaust passage extending therethrough, a conducting cross-bar for electrically interconnecting the units in the closed circuit position of the interrupter, contact structure associated with each unit to establish an arc, valve means other than the contact structure to control the flow of gas adjacent the arc, the exhaust gas for at least one of said arc extinguishing units exhausting through the bushing having an exhaust passage extending therethrough, and means whereby the cross-bar causes initial opening of the contact structure to establish arcing and permits reclosure of the contact structure while the cross-bar continues its open-

ing movement to insert two isolating gaps in the circuit.

25. In a circuit interrupter of the compressed gas type, a casing containing gas under pressure, a pair of bushings extending into the casing and having arc extinguishing units disposed adjacent their interior ends, at least one of the bushings having an exhaust passage extending therethrough, a conducting cross-bar for electrically interconnecting the units in the closed circuit position of the interrupter, contact structure associated with each unit to establish an arc, valve means other than the contact structure to control the flow of gas adjacent the arc, the exhaust gas for at least one of said arc extinguishing units exhausting through the bushing having an exhaust passage extending therethrough, and means whereby the cross-bar causes initial opening of the contact structure to establish arcing and permits reclosure of the contact structure while the cross-bar continues its opening movement to insert two isolating gaps in the circuit.

26. In a circuit interrupter, a casing, two bushings extending within the casing and having arc extinguishing units disposed adjacent their interior ends, at least one of the bushings having an exhaust passage extending therethrough, contact structure associated with each unit biased to the closed circuit position, a conducting cross-bar electrically interconnecting the two units in the closed circuit position of the interrupter, momentary engaging means for permitting initial opening motion of the cross-bar to cause initial separation of the contact structure of each unit, the contact structure reclosing following extinction of the arcs, and the continued opening motion of the cross-bar inserting two isolating gaps in the circuit.

27. In a circuit interrupter, a casing containing gas under pressure, two bushings extending within the casing and having arc extinguishing units disposed adjacent their interior ends, at least one of the bushings having an exhaust passage extending therethrough, contact structure associated with each unit biased to the closed circuit position, a conducting cross-bar electrically interconnecting the two units in the closed circuit position of the interrupter, momentary engaging means for permitting initial opening motion of the cross-bar to cause initial separation of the contact structure of each unit, the contact structure reclosing following extinction of the arcs, and the continued opening motion of the cross-bar inserting two isolating gaps in the circuit.

28. In a circuit interrupter of the compressed gas type, a casing containing gas under pressure, a bushing extending into the casing and having an arc extinguishing unit disposed adjacent its interior end, said bushing having an exhaust passage extending therethrough, contact structure including an orifice-shaped stationary contact and a movable contact separable from the stationary contact to establish an arc, an annular blast valve surrounding the movable contact and making abutting engagement with the stationary contact, disconnect means for causing operation of the blast valve prior to contact separation and making only momentary engagement therewith, and the blast of gas causing extinction of the arc exhausting out of the casing through the exhaust passage extending through said bushing.

29. In a circuit interrupter of the compressed gas type, a casing containing gas under pressure, a bushing extending into the casing and having an arc extinguishing unit disposed adjacent its

interior end, said bushing having an exhaust passage extending therethrough, contact structure including an orifice-shaped stationary contact and a movable contact separable from the stationary contact to establish an arc, an annular blast valve surrounding the movable contact and making abutting engagement with the stationary contact, disconnect means for causing operation of the blast valve, a lost-motion connection between the blast valve and the movable contact, and the blast of compressed gas causing extinction of the arc exhausting out of the casing through the exhaust passage extending through said bushing.

30. In a circuit interrupter of the compressed gas type, a casing containing gas under pressure, a bushing extending into the casing and having an arc extinguishing unit disposed adjacent its interior end, said bushing having an exhaust passage extending therethrough, contact structure including an orifice-shaped stationary contact and a movable contact separable from the stationary contact to establish an arc, an annular blast valve surrounding the movable contact and making abutting engagement with the stationary contact, a pilot valve, the disconnect means causing operation of the pilot valve, the blast of compressed gas causing extinction of the arc exhausting out of the casing through said exhaust passage extending through the bushing.

31. In a circuit interrupter of the compressed gas type, a casing containing gas under pressure, a bushing extending into the casing and having an arc extinguishing unit disposed adjacent its interior end, said bushing having an exhaust passage extending therethrough, contact structure including an orifice-shaped stationary contact and a movable contact separable from the stationary contact to establish an arc, an annular blast valve surrounding the movable contact and making abutting engagement with the stationary contact, a pilot valve, the disconnect means causing operation of the pilot valve, a lost-motion connection between the blast valve and the movable contact, and the blast of gas causing extinction of the arc exhausting out of the casing through the exhaust passage extending through said bushing.

32. In a circuit interrupter of the compressed gas type, a casing containing gas under pressure, a bushing extending into the casing having an exhaust passage extending therethrough and supporting an arc extinguishing unit within the casing, movable contact structure separable to establish an arc, a blast valve, disconnect means operable to cause opening of the blast valve, a lost-motion mechanical connection between the blast valve and the movable contact structure, and the blast of gas causing extinction of the arc exhausting out of the casing through the exhaust passage extending through said bushing.

33. In a circuit interrupter of the compressed gas type, a casing containing gas under pressure, a bushing extending into the casing and having an exhaust passage extending therethrough, an arc extinguishing unit disposed within the casing and supported by the interior end of the bushing, a stationary contact cooperable with a movable contact to establish an arc, a blast valve for admitting gas within the casing toward the stationary contact prior to contact separation, disconnect means, the disconnect means causing operation of the blast valve and making only momentary engagement therewith, and the blast of gas causing extinction of the arc exhausting out of

the casing through the exhaust passage extending through said bushing.

34. In a circuit interrupter of the compressed gas type, a casing containing gas under pressure, a bushing extending within the casing and having an exhaust passage extending therethrough, an arc extinguishing unit disposed within the casing and supported therein by the interior end of said bushing, a stationary contact cooperable with a movable contact to establish an arc, a blast valve for admitting gas within the casing toward the stationary contact, a pilot valve for dumping gas below the blast valve, disconnect means, the disconnect means causing operation of the pilot valve and making only momentary engagement therewith, and the blast of gas causing extinction of the arc exhausting out of the casing through the exhaust passage extending through said bushing.

LEON R. LUDWIG.
